(57) **CLAIM**

The ornamental design for a magnifying glass for mobile phone, as shown and described.

DESCRIPTION

FIG. 1 is a front view of a magnifying glass for mobile phone in accordance with the present invention;

FIG. 2 is a back view of the present invention illustrated in FIG. 1;

FIG. 3 is a right view of the present invention illustrated in FIG. 1;

FIG. 4 is a left view of the present invention illustrated in FIG. 1;

FIG. 5 is a top view of the present invention illustrated in FIG. 1;

FIG. 6 is a rear view of the present invention illustrated in FIG. 1; and,

FIG. 7 is a perspective view of the present invention illustrated in FIG. 1.

The portions of the magnifying glass for mobile phone shown in FIG. 2 in broken lines depict unclaimed portions of the magnifying glass for mobile phone only and form no part of the claimed design.
